UNKENSTORF

— ATTORNEY

UNITED STATES PATENT OFFICE.

ELBERT N. HARRISON, OF ERWIN, TENNESSEE.

TRY SQUARE.

Application filed January 23, 1922. Serial No. 531,176.

To all whom it may concern:

Be it known that I, ELBERT N. HARRISON, a citizen of the United States, residing at Erwin, in the county of Unicoi and State 5 of Tennessee, have invented certain new and useful Improvements in Try Squares, of which the following is a specification.

This invention has reference to try squares and its object is to provide a carpenter's 10 instrument for use in connection with building operations and more particularly with reference to framing wooden buildings.

In accordance with the invention, there is provided a right angular blade carrying both 15 members of the blade which are longitudinally slotted and provided with handle members attached to the right angular members by means of thumb screws whereby the handle members may be adjusted longitudinally 20 of the slots.

The blades making up the square are provided with gradations representing various pitches to which timbers used in the framing are to be cut. Furthermore, handle 25 members are provided whereby the timbers may be marked off to guide a carpenter in sawing the timbers into the desired shape, and various pencil gages are provided to assist the workmen in the proper laying out 30 of the timbers, and other guides are provided to assist the workmen.

The invention will be best understood from a consideration of the following detailed description taken in connection with 35 the accompanying drawings forming part of the specification, with the understanding that the invention is not confined to any strict conformity with the showing of the drawings, but may be changed and modified 40 so long as such changes and modifications mark no material departure from the salient features of the invention as expressed in the appended claims.

In the drawings:—

Figure 1 is a plan view of the try square. 45

Fig. 2 is a plan view of the try square, on the opposite face from that shown in Fig. 1.

Fig. 3 is a detail of the structure hidden 50 in Fig. 1.

Fig. 4 is a longitudinal section of one of the handle structures.

Fig. 5 is a plan view of the structure used as a gage for boring sash pulleys.

Fig. 6 is a plan view showing the arrange- 55

ment of the parts for laying off timbers other than the arrangement shown in the other views.

Referring to the drawings there is shown a right angular try square 1, which, as is customary, is made of thin sheet metal with a long blade 2 and a short blade 3, formed integrally with the long blade and extending at right angles from one end. The blade or member 2 has an intermediately located central slot 4 extending from a point near the center of the blade to and around the angle and along the blade 3 the slot being wide enough to accommodate the stem 5 of a thumb screw 6, carried by a split handle 60 member 7, having a bearing 8 at one end in the handle 7 and a nut bearing 9 at the other side in the handle 7, such handle being usually constructed of wood and indicated at 10. The thumb screw 6 with its stem 5 65 and the nut 9 provide means for clamping the handle 7 in adjusted position on the blade 3.

The outer end of the blade 3 is cut off at an angle indicated at 11 to determine certain 70 angles of cut in building construction.

To protect the outer end of the handle 10 and also of other handle structures used in connection with the square, metal plates 12 75 are embedded in the outer end of the handle and held thereto by a rivet 13.

To facilitate the marking off of timbers, the blade 3 of the gage is provided with a regular series of through slots between the slot 4 and its inner edge 14 which may be 80 spaced at regular intervals to permit the passage of a pencil point and therefore constitute a pencil gage.

The same blade 3 is provided with a key-hole slot 15 and with a perforation 16 for 85 marking off the relative positions of the key-hole slot and knob spindle for a mortise lock.

Laid off on the arm 2 of the square on one face thereof, are numerous lines 17, 18 100 and 19, showing common rafter pitches, and hip and valley pitches for roofs and side cuts for jacks of any pitch.

About midway of the length of the longer blade 2 of the try square and projecting at 105 right angles from the edge thereof remote from the arm 3, is a right angularly extending blade 20 similar to the arms 2 and 3. The blade 20 is a short blade with a central longitudinal slot 21, the inner edge of which does 110

not extend into the blade 2, but terminates on a line with its outer edge, and is useful in cutting two by four inch timbers.

The outer or free end of the blade 20 is 5 bevelled off at an angle 22 determining the window sill slope.

The blade 2 has a second longitudinal slot 2^a therein, which begins at a point near the outer end and terminates before reaching the 10 end of the slot 4, at a point in line with the near edge of the blade 20.

At the end of the blade 2 remote from the blade 3 there is located a handle 23 clamped in place by a thumb screw 24 similar to the 15 thumb screw 6 and capable of engaging in the blade 2. Each of the thumb screws 6 and 24 bind the handles 7 and 23 firmly to the blades of the try square in any one of the 20 various adjusted positions. These thumb screws are made to engage the handles with a snug fit and the handles may be adjusted along the intermediate slots 2^a in the blade in various angular relations thereto, and one of the handles may be applied 25 to the angular extension 20 of the blade 2.

One long edge of the handle 23 has a bevelled portion 25 with gradations 26 to facilitate the reading of such gradations.

The outer end of the blade 2 on one face 30 thereof is furnished with a protractor scale 27 and at the center of said scale, the blade 2 is furnished with a perforation 28. The purpose of the scale 27 is to facilitate the reading of the angles at which the handle 35 23 is set.

Adjacent the scale 27, in the longitudinal center of the blade, are perforations 29, providing a gage for use when cutting an opening in a window frame for the insertion of a 40 sash pulley.

The operation is as follows:—The end of the blade 2 is placed against the under side of the top of the window frame and in the groove in which the sash travels, a pencil 45 mark is then made on the frame thru the upper end of the slot 2^a and another thru one of the holes 29, according to the size pulley to be used, from the end of the slot to the first hole, if a small pulley is to be used, 50 or from the end of the slot to the second hole if a medium sized one is to be used and so on. These points are then used as centers for the bit when cutting the slot. In using this gage the distance from the top of the 55 frame down to the top of the pulley slot is accurately measured upon both sides.

Hexagon, octagon and other cuts are indicated on the blade 3 by appropriate lines 30.

What is claimed is:—

60 1. A square of the character described comprising, a long blade, a short blade integral therewith and extending at right angles from one end thereof, and a second short blade integral with and extending at right angles to said long blade at a point in-

termediate its ends and in a direction opposite to said first mentioned short blade, said long blade being provided with a pair of central longitudinal slots and each of said short blades being provided with a central longitudinal slot, the slot in the short blade adjacent the end of the long blade merging into one of the slots in said long blade. 70

2. A square of the character described comprising, a long blade, a short blade integral therewith and extending at right angles from one end thereof, a second short blade integral with and extending at right angles to said long blade at a point intermediate its ends and in a direction opposite to said first mentioned short blade, said long blade being provided with a pair of central longitudinal slots and each of said short blades being provided with a central longitudinal slot, the slot in the short blade adjacent the end of the long blade merging into one of the slots in said long blade, and means common to either of said blades adapted to be adjusted thereon at any desired angle with respect to the blade, and constituting a handle member. 80

3. A square of the character described comprising, a long blade, a short blade integral therewith and extending at right angles from one end thereof, and a second short blade integral with and extending at right angles to said long blade at a point intermediate its ends and in a direction opposite to said first mentioned short blade, said long blade being provided with a pair of central longitudinal slots and each of said short blades being provided with a central longitudinal slot, the slot in the short blade adjacent the end of the long blade merging into one of the slots in said long blade, said long blade further provided with spaced apertures positioned between the terminus of one of said slots and the free end of said blade, said apertures associated with said slot constituting a gage for cutting pulley 100 openings of varying sizes. 105

4. A square of the character described comprising, a long blade, a short blade integral therewith and extending at right angles from one end thereof, and a second short blade integral with and extending at right angles to said long blade at a point intermediate its ends and in a direction opposite to said first mentioned short blade, said long blade being provided with a pair of central longitudinal slots and each of said short blades being provided with a central longitudinal slot, the slot in the short blade adjacent the end of the long blade merging into one of the slots in said long blade, and means common to either of said blades adapted to be adjusted thereon at any desired angle with respect to the blade, and constituting a handle member, said long blade further having marked thereon vari- 110 115 120 125 130

ous scales cooperating with said handle member for determining various degrees of rafter pitch.

5. A square of the character described comprising, a long blade, a short blade integral therewith and extending at right angles from one end thereof, a second short blade integral with and extending at right angles to said long blade at a point intermediate its ends and in a direction opposite to said first mentioned short blade, said long blade being provided with a pair of central longitudinal slots and each of said short blades being provided with a central longitudinal slot, the slot in the short blade

adjacent the end of the long blade merging into one of the slots in said long blade, means common to either of said blades adapted to be adjusted thereon at any desired angle with respect to the blade, and constituting a handle member, said handle member being formed of two parts between which the blades are adapted to be moved, and a clamping screw thru one end of said handle and adapted to pass thru said slots to guide and hold the handle on the blade. 20 25

In testimony whereof, I affix my signature hereto.

ELBERT N. HARRISON.
